EDWARD E. NEIDNER, OF MILWAUKEE, WISCONSIN

MOP WRINGER

Application filed December 11, 1930. Serial No. 501,500.

This invention relates to mop wringers.

Numerous attempts have been made to provide a satisfactory wringer which would meet the demands and requirements of the public.

5 These attempts have encompassed several types of wringers; one in which the mop is passed between squeezing rollers, another in which a mop is twisted, and the third in which water is squeezed from the mop by 10 means of the application of pressure. Of these three well known types the last mentioned is by far the most effective, by reason of the fact that little or no damage is done to the mop by repeated squeezing operations.

15 The general aim of the present invention is the provision of improved means in the last named type of wringer for applying a squeezing pressure to two sides of the wringer by moving a plurality of opposed plates toward 20 each other.

One object is the provision of a mop wringer which is simple in construction, durable in service, effective in operation, and inexpensive to manufacture.

25 Other objects and advantages will appear from the following description of an illustrative embodiment of the present invention.

In the drawings:

Fig. 1 is a vertical sectional view taken on the line 1—1 of Fig. 2.

Fig. 2 is a vertical sectional view taken at right angles to that of Fig. 1 on the line 2—2 of Fig. 1.

Fig. 3 is an end elevational view of the wringer with parts broken away to show the relative position of the several parts.

Fig. 4 is a side elevational view, with parts broken away, to show the relative position of the several parts when the wringer is in operating position.

Fig. 5 is a horizontal sectional view taken on the line 5—5 of Fig. 4.

In the illustrative embodiment of the invention, shown in the accompanying drawings, the wringer comprises a pair of end plates 10 which are retained in spaced relationship by a plurality of tie rods 11. Each plate 10 carries a downwardly directed ear 12 which is in spaced relation with the edge of the plate which lies beneath. These ears

serve as means for retaining the wringer in position upon the pail or receptacle with which it is used. A pair of side plates 13, which are perforated as at 14, are secured to the tie rods 11 by any suitable means such as welding. These plates together with the end plates serve to form an open bottomed receptacle for receiving the mop.

A pressure member 15 which is provided with perforations 16 serves to form a movable bottom to complete the mop receiver. The plate 15 is secured to and carried by a pair of spaced bars 17 which extend through and are guided in vertically disposed slots 18 in the end plates 10. Motion is imparted to the plate 15 in a manner to be hereinafter more specifically described.

A second pressure member comprises a pair of rockable plates 19 which are retained between the end plates 10 and are movable into and out of the mop retaining basket. Each of the plates 19 is provided with a reinforcing web 20 and a cut-away portion 21 disposed midway along its inner edge to provide an opening through which the mop handle may extend.

A pair of laterally spaced trunnions 22 and 23 extend outwardly from each end of the plates 19. These trunnions 22 and 23 extend through plates 10 and are guided in cam slots 24 and 25, respectively, in the plates 10. The slots 24 and 25 are positioned in such manner as to direct the plates 19 inwardly and downwardly upon movement in one direction and upwardly and outwardly upon movement in the other direction.

By reason of this condition it is possible to provide an unimpaired opening in the receptacle for receiving the mop to be wrung. Motion is imparted to the plates 19 simultaneously with the movement of the member 15 in a manner about to be described.

The mechanism for imparting motion to the plates 19 and the bottom member 15 of the receptacle comprises a bar 26 which is journalled in the plates 10 preferably above and to one side of the mop basket. This bar is journalled for rotation in the end plates and is provided with extended ends 27 to receive plates 28 which carry actuating pins 29 and 30. The pins 29 extend outwardly from

the plates 28 through horizontally disposed slots 31 in ears 32 on sliding brackets 33. The brackets 33 are provided with horizontally disposed portions 34 at their lower extremities. The bars 17 carried by the member 15 of the mop basket are secured to the portions 34 of the brackets 33. The upper end of the plates 33 are guided by pins 35 which cooperate with slots 36 formed in the upper portions of the brackets 33. The pins 30, which extend inwardly from the plates 28, cooperate with horizontally disposed slots 37 fashioned in ears 38 formed on brackets 39. Slots 40 in the brackets 39 cooperate with the pins 35 and similar slots 41 cooperate with pins 42 anchored in the side bracket 10 so as to guide the members 39 in their vertical movement. The lower extremities of the members 39 are provided with arms which extend outwardly and downwardly. Cam slots 43 are formed in the arms in such a manner as to encompass the pins 22 and 23 formed on the ends of the plates 19 and projected through the slots 24 and 25 in the end plates 10.

25 The bar 26 is provided with a handle socket 44 adapted to receive and retain a handle 45 in any provided manner. When the handle 45 is swung from the position shown in Fig. 3 to that shown in Fig. 4 the plates 28, carried by the end of the bar 26, are rotated and the pins 29 are swung rearwardly and upwardly while the pins 30 are swung forwardly and downwardly. As previously described, 30 the pins 29 and 30 cooperate with slots 31 and slots 27 respectively in the members 33 and members 39. As the pins 29 are drawn rearwardly and upwardly they impart movement to the members 33, and in so doing raise the bottom member 15 of the mop basket. Simultaneously with this motion the pins 30, which are acting in the slots 37, move the members 39 downwardly and in so doing impart to the pins 22 an inward movement along the horizontally disposed portion of the slots 43 and the downwardly inclined portion of the slots 24. As the members 39 start their downward movement the pins 23 remain in the horizontally disposed upper ends of the slots 25 until such time as the extremities of the pins 23 engage the horizontal portion of the slot 43. At this time the follower plates 19 have reached a substantially horizontal position. Continued pressure will 45 force the plates 19 downwardly in opposition to the upward movement of the member 15. It will thus be noted that a mop which has been positioned within the receptacle will be exposed to pressure of the plates 19 and member 15 simultaneously and by reason of this fact, the water will be quickly and forcibly ejected from the mop.

50 When the mop has been exposed to sufficient pressure to free it of all excess water, the handle 45 may be swung back to the posi-

tion shown in Figure 3 of the drawings to withdraw the plates 19 from their mop engaging position and to permit ready removal of the mop from the basket.

It will readily be seen from the foregoing description that a simple and effective wringer has been provided in which the several elements are effectively combined to give the necessary mechanical advantage to exert sufficient pressure upon the mop to free it of water by the simple and easy manipulation of handle 45. The construction of the wringer is such that ready application and removal of the wringer is possible by reason of the fact that the interior of the mop receiver is free from moving parts. The several guide and cam slots formed in the end plates of the wringer serve to permit the application of the actuating means to the outer walls of the plates in a manner which facilitates their free and unimpeded movement. By virtue of the fact that all of the actuating means are mounted on the end plates, it is possible to provide a small and compact device of unusual strength and durability.

Various changes may be made in the embodiment of the invention hereinabove specifically described without departing from or sacrificing any of the advantages of the invention as defined in the appended claims.

I claim:

1. A mop wringer comprising a mop receiver, a pair of pressure members both movable therein toward and from each other, one of said pressure members comprising a pair of rockable plates, and means for rocking said plates and for actuating both of said pressure members to squeeze a mop therebetween.

2. A mop wringer comprising a mop receiver, a pair of pressure members both movable therein toward and from each other, one of said pressure members comprising a pair of rockable plates, a handle, and means actuated by said handle for rocking said plates and for moving said pressure members to squeeze a mop therebetween.

3. A mop wringer comprising a mop receiver, a pair of pressure members both movable therein toward and from each other, one of said pressure members comprising a pair of rockable plates, means for rocking said last named plates in said mop receiver to permit ready insertion of a mop, a handle, and means actuated by said handle for actuating said first named means and for moving said pressure members to squeeze a mop therebetween.

4. A mop wringer comprising a perforated mop receiver, a pair of pressure members both movable therein toward and from each other, one of said pressure members comprising a pair of plates, said plates being rockable in said mop receiver, projections carried by said pressure plates, cam slots in said re-

ceiver for receiving and guiding said projections, a movable pressure plate forming a part of said mop receiver, and means for actuating said pressure members to squeeze a 5 mop therebetween.

5. A mop wringer comprising a pair of end frames, a pair of vertically disposed perforated plates between said end frames, a movable pressure plate cooperating with said perforated plates to form a mop receiver, a pair of 10 rockable pressure plates carried by said end frames, said last named plates forming a closure for said mop receiver, and means for simultaneously moving said first named 15 pressure plate and said pair of pressure plates to squeeze a mop therebetween.

6. A mop wringer comprising a pair of end frames, a pair of vertically disposed perforated plates between said end frames, a 20 movable bottom pressure plate cooperating with said perforated plates to form a mop receiver, guide slots in said end frames for directing the movement of said pressure plate between said perforated plates, a pair of top 25 pressure plates, a plurality of pins on said plates, said pins extending through said end frames, cam slots in said end frames for directing the movement of said last named pressure plates, and means for simultaneously 30 effecting movement of said bottom pressure plate and said pair of top pressure plates to squeeze a mop therebetween.

7. A mop wringer comprising a pair of end frames, a pair of vertically disposed perforated plates between said end frames, a 35 movable pressure plate cooperating with said perforated plates to form a mop receiver, guide slots in said end frames for directing the movement of said pressure plate between 40 said perforated plates, a pair of top pressure plates, a plurality of pins on said plates, said pins extending through said end frames, cam 45 slots in said end frames for directing the movement of said last named pressure plates, a handle carried by said wringer and means responsive to initial movement of said handle for causing said last named pressure plates to swing inwardly and means responsive to the 50 continued movement of said handle to simultaneously effect movement of said first named pressure plate and said pair of pressure plates for exerting pressure upon a wringer to 55 expel water therefrom.

8. A mop wringer comprising a pair of end 55 frames, a pair of vertically disposed perforated plates between said end frames, a movable pressure plate cooperating with said 60 perforated plates to form a mop receiver, guide slots in said end frames for directing the movement of said pressure plate between 65 said perforated plates, a pair of top pressure plates, a plurality of pins on said plates, said pins extending through said end frames, cam 70 slots in said end frames for directing the movement of said last named pressure plates,

a movable bracket carried by said end frames and means for connecting said bracket to said first named pressure plate, a second bracket carried by said end frames, guide slots in said brackets, means carried by said end frames 75 for cooperation with said guide slots, cam slots in said last named bracket, said last named slots cooperating with said pins on said top pressure plates, a handle carried by said mop wringer and means cooperating therewith to effect movement of said brackets, the initial movement of said last named bracket causing said pressure top plates to swing inwardly and into said mop receiver and continued movement thereof serving to effect 80 simultaneous movement of said first named pressure plate and said pair of pressure plates to effect a squeezing pressure upon a mop to expel water therefrom.

In witness whereof, I hereunto subscribe 85 my name this 6th day of December, 1930.

EDWARD E. NELDNER.
